COMBINATION AIR CONDITIONING AND HEATING UNIT CASING

Kenneth P. Schory, Bensenville, Ill.

Application May 28, 1956, Serial No. 41,690

Term of patent 7 years

(Cl. D62—4)

The figure is a front perspective view of a combination air conditioning and heating unit casing showing my new design. The sides and rear of the casing are plain.

I claim:

The ornamental design for a combination air conditioning and heating unit casing substantially as shown and described.
